UNITED STATES PATENT OFFICE.

THYGE NELSEN, OF CHICAGO, ILLINOIS.

ELECTRIC-LAMP FIXTURE.

1,124,939.

Specification of Letters Patent.

Patented Jan. 12, 1915.

Application filed May 27, 1914. Serial No. 841,217.

To all whom it may concern:

Be it known that I, THYGE NELSEN, a citizen of the United States, residing at Chicago, in the county of Cook and State of Illinois, have invented certain new and useful Improvements in Electric-Lamp Fixtures, of which the following is a specification.

My invention relates to improvements in electric lamp fixtures and has especial reference to side brackets and ceiling fixtures and the like, which are intended for out of doors exposure and which are weather resistant and water proof.

Some of the general objects of my invention are to provide a lamp bracket, for porch lights, such as are usually secured to side walls of a door or the main entrance of a building, or used in other like exposed situations, so designed and arranged that it may readily be made heavy, of cast iron, quickly and inexpensively assembled, without requiring a great deal of tooling, and adapted to permit of convenient wiring, after it has been installed.

Another object is to so arrange the parts that moisture, due to leaks or condensation cannot remain in the hollow portions thereof, thereby to destroy the structure by freezing and by breaking down the insulation of the electric conducting portions.

Other and more specific objects of my invention will become readily apparent to persons skilled in the art from a consideration of the following description when taken in conjunction with the drawings, wherein—

Figure 1 is an elevation of the fixture showing parts in section. Fig. 2 is a transverse section, taken on line 2—2 of Fig. 1. Fig. 3 is an enlarged sectional view, showing the manner of securing the lamp socket to the globe holding support. Fig. 4 is a modification showing another method of securing the socket, of a different type, to the support.

In all the views the same reference characters are employed to indicate similar parts.

In my United States Patent No. 1,088,165 dated February 24th, 1914, I have shown and claimed a fixture of a generally similar type to that sought to be patented herein, but my present invention contains refinements not present in my former patent.

In the present embodiment 5 is a vertical wall containing a bracket support 6, which

may be a pipe or the like, for securing the fixture thereto.

7 is a hollow stem, screw threaded to the support 6, for maintaining the fixture in its position.

8 is a canopy surrounding the stem and secured in place thereon by the friction screws 9—9.

The stem 7 terminates in an enlarged end or head 10 which is transversely perforated, 65 on each of its sides, by an angular opening 11. The opening is shown generally round for the most part being tangentially cut away at opposite diameters to prevent a similar formed object, that may be inserted 70 within the opening, from being turned around or rotated therein. The stem 7 is also provided on one of its sides within the canopy 8, with an opening 12, having preferably rounded edges to prevent chafing of 75 the electric wires.

A cup shaped socket-receiving member, 13 is provided with an outwardly flanged edge 14, near its top, and with a cylindrical projection or hollow boss 15 extending from its 80 bottom. The cross section of the cylindrical projection 15 is substantially the same as the openings 11 provided in the head 10 of the stem 7, as shown in Fig. 2, so that when the extension 15 is placed within either of the 85 openings 11—11, the cup portion 13 cannot be rotated, with reference to the head 10, and as both ends of the enlargement are provided with openings 11, the cup member 13 may be placed in either of the openings so 90 that the lamp which is supported on the cup shaped member 13 may hang downwardly or may be supported, as shown in the drawings.

Projecting from the cylindrical portion 15 is a nipple 16, which may be an integral 95 portion of the part 15 or it may be a separate portion, such as a threaded pipe nipple, secured thereto as by screw threads, or the like. The nipple 16 projects toward the opening in the lower portion of the head 10, 100 for screw threaded engagement with the nut 17. The nut 17 is provided with a shoulder 18 and a cylindrical guide portion 19 which enters the opening 11 on the opposite side of the enlarged head 10, and since the guide 105 portion 19 is not angular but round in cross section, the nut may be turned within the opening 11 to secure the parts to the head. Within the cylindrical projection 15 is an opening 20 which is relatively large, bound- 110

ed by walls with tapered and rounded surface so as to prevent chafing of the wires and to permit easy threading of the wires through the cup 13 and into the hollow stem 7 and through the opening 12 made therein after the device has been installed. The nut 17 is hollow and is provided with a drain opening 21 at the bottom of the hollow portion, to permit the water which may be received in the interior through the thimble 16 or through the interior of the cup shaped portion 13 to drip out. A similar opening 22 for the same purpose, is provided in the lower portion of the head 10, and another opening 23 of generally similar character for the same purpose, is provided in the globe holder 24. The globe holder 24 is counter sunk, to provide a recess for the reception of the flange 14, of the cup member 13, the parts being held together by means of screws 25 of which a suitable number may be employed. The globe receiving portion of the holder 24 may be of varying diameter, to accommodate the different styles, sizes and types of globes, 26. One of the important features of my invention is the perforate raised socket-holding portion 27, of the holder 24. The raised portion 27 is provided with an inwardly projecting flange 28 to provide a rim against which to secure the socket 29.

The socket 29 of a well known type consists of the major portion 29^a and the minor portion 29^b, the latter being screw threaded in the shell 30, to hold the parts together, and between the parts the flange 28 of the globe holder is included. The socket 29^b of another type, may be secured to the flange 28, by means of a thin ring 31 which normally is concavo-convex and in the position shown in dotted lines at 32 and which, after the parts have been placed in position on the globe holder 24, is flattened out so as to decrease its internal diameter and thereby produce a gripping effect upon the body part of the socket 29^b to hold the socket securely in place, with reference to the globe holder.

In assembling the device, after the parts including the cup 13 have been placed in position upon the side walls 5, the screws 25 are taken from the globe holder and the socket 29 or 29^b, as the case may be, is securely fixed in the elevated portion 27 of the globe holder, in the manner heretofore described. The wires 33 are then attached to the socket, slightly curved and threaded through the relatively large opening 20, and along the hollow stem 7, and out through the opening 12. The parts are so relatively large and the openings are so amply sufficient for the purpose that there is no difficulty in threading the wires 33 through the said parts and out through the opening 12, readily accessible when the canopy 8 is loose

upon the stem 7, and pushed toward the enlarged head 10, to permit an opening between the edge of the canopy and the vertical wall 5. After this has been done, the globe holder, 24 is placed back in position 70 over the flange of the cup so that the counter sunk portion thereof registers with the flange 14 of the cup 13, and the screws are placed in position to hold the cup 13 and the globe holder 24 together. The globe 26 75 may then be placed on the holder and secured thereto by the screws 26^b.

The lamp 33 is adapted to be screwed into the threaded shell 30, of the socket 29, before the globe 26 is placed in position on 80 the globe holder 24.

While I have herein shown a single embodiment of my invention, for the purpose of clear disclosure, it is evident that changes may be made therein, within the spirit and 85 intendment of the claims, without departing from the scope thereof.

Having described my invention, what I claim is:—

1. A lamp fixture comprising a cup-shaped socket-containing support, having a flange extending laterally therefrom; a globe holder having a concentric recess to receive said flange; and means to secure the parts together, said holder having also a 95 concentric, centrally raised perforated portion within which to secure a socket.

2. A lamp fixture comprising a cup-shaped socket-containing support, having a flange extending laterally therefrom; a 100 globe holder, having a concentric recess to guide and to receive said flange; screws to secure the parts together, said holder also having a concentric, centrally perforated portion, raised above the floor of the globe 105 receiving portion having an inwardly projecting flange, and means, on each side of said flange to secure the socket to said globe holder.

3. A lamp fixture comprising a hollow 110 socket-receiving cup, below the globe holder; a separable globe holder secured thereto, having a centrally raised concentric portion, carrying socket attaching means, and means to secure a socket to said raised portion.

4. A lamp fixture comprising a hollow socket-receiving cup, below the globe holder; a separable globe holder, secured thereto, having a centrally raised concentric portion, 120 carrying socket attaching means and having a lower portion upon which to rest the globe, said lower portion being perforated to provide a drain and means to secure a socket to said raised portion whereby the open end 125 thereof is raised above the globe resting portion.

5. In a lamp fixture the combination of a hollow stem, having an enlarged hollow head transversely perforated with angular 130

openings, one at each end; a socket-receiving cup having an integral, hollow, angular stem, projecting into said head, and having a lateral opening, within said head; a separable globe holder, having a concentric raised portion to which to attach a socket; socket attaching means; means to connect said holder and cup together, after said fixture has been installed and means to secure

10 said cup to said stem.

6. A lamp fixture comprising a hollow stem, terminating in a hollow head, having vertically alining angular perforations; a socket-receiving cup having an integral, hollow, angular boss projecting into one of said openings; a thread engaging holding

device, projecting into the other vertical opening in said head; a separable globe holder having a vertical flange and a floor upon which to rest the globe and a centrally 20 perforate, concentric, raised portion to receive and hold a socket, said floor being perforated to drain water from said holder, and means to separably secure said globe holder to said cup.

25 In testimony whereof I hereunto set my hand in the presence of two subscribing witnesses.

THYGE NELSEN.

In the presence of—

STANLEY W. COOK,

MARY F. ALLEN.
